DRIFT

Francis J. Woodruff, Detroit, Mich., assignor of
one-half to John Thomas Gilmer, Detroit,
Mich.

Application April 7, 1942, Serial No. 438,017

2 Claims. (Cl. 254—104)

This invention relates to drifts of the type used by mechanics, commonly known as key drifts, and the principal object is the provision of a drift of new and novel character which eliminates certain disadvantages of conventional types of such drifts.

Objects of the invention include the provision of a drift which when employed for removing a gear, pulley or the like from a shaft it will not cause the gear or pulley to cock on the shaft and thereby resist removal therefrom; the provision of a drift of the character described by the use of which the pressure applied by the drift to the piece to be removed thereby may be applied in such a manner as to reduce the bending force on the piece as compared to a conventional drift; the provision of a drift of the character described so constructed as to eliminate the tendency of conventional types of drifts to slip out between the parts being separated thereby; and the provision of a drift of the character described that is double wedge shaped in conformation whereby to enable certain advantages to be obtained thereby and certain disadvantages of conventional types of drifts to be dispensed with.

The above being among the objects of the present invention the same consists in certain novel features of construction and combinations of parts to be hereinafter described with reference to the accompanying drawing, and then claimed, having the above and other objects in view.

In the accompanying drawing which illustrates suitable embodiments of the present invention and in which like numerals refer to like parts throughout the several different views,

Fig. 1 is a perspective view illustrating a pair of pulleys mounted on a shaft and illustrating the use of a drift constructed in accordance with the present invention to remove one of the pulleys from the shaft and a drift constructed in accordance with the present invention to remove a key securing the other of the pulleys to the shaft;

Fig. 2 is an enlarged perspective view of a left-hand drift constructed in accordance with the present invention;

Fig. 3 is a transverse sectional view taken on the line 3—3 of Fig. 2;

Fig. 4 is a perspective view of a righthand drift constructed in accordance with the present invention;

Fig. 5 is a transverse sectional view taken on the line 5—5 of Fig. 4;

Fig. 6 is a perspective view of a combined right

and left hand drift constructed in accordance with the present invention; and,

Fig. 7 is a transverse sectional view taken on the line 7—7 of Fig. 6.

5 Drifts of the type herein under discussion are forms of wedges usually having a constant width and varying in thickness. They are conventionally formed from steel and are usually of hardened character. They are conventionally employed between a pair of machine parts which it is desired to separate from one another and in employing the same the small end of the drift is inserted between the parts and pressure is applied to the thick end of the drift, usually by a 10 hammer or equivalent means, thus to force the drift between the parts and cause them to be wedged apart. Such drifts are commonly called key drifts for the reason that one of their major uses is to remove the driving keys between a shaft and some part fixed to it for rotation, the keys in such case usually being provided with a head projecting outwardly beyond the surface of the shaft between which and the part mounted on the shaft the drift may be inserted and driven. Such drifts also find wide use in removing pulleys, gears, or like objects from shafts, this being conventionally accomplished by inserting and driving the drift between the hub of the pulley, gear, or the like and some parts fixed 15 to the shaft and providing a face lying in a plane perpendicular to the axis thereof.

20 In the past it has been conventional practice to form such drifts of rectangular cross-sectional configuration. As a result, if the parts between which the drift is forced are worn or battered 25 the wear or battering has usually occurred radially outwardly from the surface of the shaft on which they are mounted with the result that there is a tendency for the drift to be displaced 30 radially outwardly between the parts upon pressure being applied thereto before a sufficient amount of pressure can be exerted longitudinally through the drift to separate the parts axially of the shaft. Where this condition exists the removal of a part from a shaft often becomes an 35 exasperating job in view of the difficulty in maintaining the drift in that position to which it is required to be maintained in order to effect its purpose. If the parts between which the drift 40 is positioned are provided with surfaces which are not worn or battered and lie in planes perpendicular to the axis of the shaft, then there 45 is a tendency for the drift to exert its pressure between the radially outward parts of such surfaces and particularly where the part to be re-

moved is a gear or pulley having a relatively limited axial length or dimension, the pressure of the drift has a tendency to cock the gear or pulley on the shaft and to cause its axially outer edges to dig into the surface of the shaft and resist movement thereof on the shaft under the force of the drift.

The disadvantages above described in connection with drifts of conventional construction is obviated in accordance with the present invention by so forming such drifts not only are they wedge-shaped longitudinally as in conventional drifts but additionally they are more or less wedge-shaped in transverse section. In other words they are similar to conventional drifts in being longitudinally tapered to wedge-like form, but additionally the transverse dimensions of one of the side faces of the wedge are uniformly less over the length thereof as compared to the corresponding dimensions of the other side face of the wedge, thus forming the drifts with one edge formed by the juncture of two surfaces disposed at less than 90 degrees with respect to each other.

With a drift formed in accordance with the present invention and as above described, that edge of the drift formed by the surfaces disposed at less than 90 degrees with respect to each other is applied to the shaft at the junction between the shaft and the part to be removed therefrom and then pressure is applied to the drift in the usual way. Because of the angularity of the two sides referred to no pressure is exerted by the drift upon the part to be removed from the shaft radially outwardly of its point of contact with the shaft and consequently no tendency to cock the part on the shaft occurs to resist removal of the part. Furthermore, because the line of contact between the parts to be removed from the shaft and the drift is limited to a line intersecting the surface of the shaft and perpendicular to the line of contact between the drift and the shaft, and the drift is free of contact with the part to be removed radially outwardly of such line of contact between the drift and the shaft, there is no tendency of the drift to slip radially outwardly with respect to the part to be removed from the shaft. Thus two of the major disadvantages of conventional drifts are obviated.

The same general remarks apply where the drift is employed to remove a key from between a shaft and a part mounted thereon as in such case the sharp edge of the drift, that is, that edge formed by the junction of the two surfaces located at less than 90 degrees with respect to each other, is placed against the head of the key at its point of junction with the body of the key, this reducing any cocking tendency between the drift and the key to a minimum and eliminating the tendency of the drift to slip radially outwardly of the shaft with respect to the head of the key.

From the above it will be observed that it is the preferred practice in the employment of a drift constructed in accordance with the present invention to always place the sharp edge of the drift against the part which is to be removed from another part and as close to the area of junction of the parts as is practical under the circumstances. Actual practice has demonstrated that drifts constructed in accordance with the present invention are much more efficient, are longer-lived and permit them to accomplish their intended result in a quicker and easier manner

than conventional drifts as heretofore constructed.

Drifts constructed in accordance with the present invention may be righthanded, lefthanded, or may be constructed to include a combination of both. They are designated either as right-handed or lefthanded depending upon which side of the drift is reduced in dimensions as compared to the opposite side. Where such drift is combined to function as both a right and a left-handed drift then it is usually made of a greater width than either a righthanded or a lefthanded drift and its cross-sectional dimensions, measured in the direction of its thickness is decreased towards its longitudinal center line on one face thereof, thus providing two sharp edges in a single drift.

Referring now to the accompanying drawing, in Fig. 1, in order to illustrate the application of the invention, a cylindrical shaft is indicated at 10 and as having a pulley 12 mounted on one end thereof and a pulley 14 mounted adjacent the other end thereof. The pulley 12 is shown fixed for equal rotation with respect to the shaft 10 by means of a key 16 received in the groove of key-way 18 in the shaft 10 and in a complementary groove or key-way (not shown) in the bore of the pulley 12. The outer end of the key 16 is provided with a radially projecting head 20 in accordance with conventional practice. Where a key such as 16 is employed the pulley 12 will conventionally have a sliding fit on the shaft 10 and will ordinarily be locked in position by means of the key 16 so that upon removal of the key 16 the pulley 12 may be removed from the shaft. The pulley 14 may be assumed to have a light press fit upon the shaft 10 and in such case a key such as employed in connection with the pulley 12 is neither necessary nor desirable unless the pulley is to be subjected to extremely heavy turning forces.

In order to remove the key 16 from the shaft 10 and pulley 12 a drift is inserted between the head 20 of the key 16 and the hub of the pulley 12 and the drift is driven as by means of a hammer 22 between these parts, the key 16 thus being forced axially along the shaft from between the shaft and the pulley 12. Where it is desired to remove a pulley such as 14 from the shaft 10 the shaft will usually be provided with a collar such as 24 fixed to the shaft at one side of the pulley, or be provided with a radial shoulder corresponding with the end surface of the sleeve 24 and between which and the hub of the pulley 14 the small end of the drift may be inserted as shown and driven home as by means of a hammer 22 to cause the pulley 14 to be displaced axially along the shaft 10.

If in the case shown in Fig. 1 the drift is a conventional rectangularly sectioned drift and the inner radially disposed face of the head 20 of the key 16 is worn or battered it will be appreciated that in driving the drift between the head of the key and the pulley 12 there will be a tendency for the drift to slip radially outwardly between the part that it is intended to separate. On the other hand, if the surfaces referred to are square then there will be a tendency for the drift to bear against the radially outer edge of the inner face of the head 20 of the key 16 and to force the axially outer radially inner edge of the key 16 into the metal at the bottom of the key-way 18 thus to dig into such metal and to increase the resistance to its removal.

In the case of the pulley 14 if the drift em-

ployed is a conventionally rectangular sectioned drift and the cooperating faces between which the drift is received are not worn or battered so as to engender slipping out of the drift, then there will be a tendency of the drift to bear against the radially outer edge of the hub of the pulley 14 and to cause the pulley to cock on the shaft 10 so that its axially outer edge will tend to dig into the surface and resist removal.

The drift 30 indicated in Fig. 1 between the pulley 14 and the sleeve 24 is a lefthand drift constructed in accordance with the present invention as illustrated in greater detail in Figs. 2 and 3. Referring to these figures it will be appreciated that the drift 30 there shown is formed from a piece of metal, preferably steel and preferably hardened, is of an equal width throughout its length which is preferable but not necessary in the particular form shown, it tapers, in the particular form shown, uniformly in thickness from one end to the opposite end thereof, and in accordance with the present invention the thickness tapers in transverse section from one side thereof to the opposite side thereof so that the lefthand face thereof as viewed in Figs. 2 and 3 is uniformly of less thickness, or of less dimensions transversely of its length, throughout its length than the thickness or corresponding dimensions of the righthand face thereof at a corresponding position in the length of the drift. The bottom face 32 of the drift 30 is located in a plane perpendicular to both side faces 34 and 36 but the angularity between the side face 36 and the top face 38 as viewed in cross-section and as illustrated in Fig. 3 is less than 90 degrees so as to form a sharp edge 40. This feature imparts a trapezoidal section to the drift. The angularity between the faces 36 and 38 in sectional view may, of course, vary between greater or lesser limits, but if arranged between 75° and 80° satisfactory results will usually be obtained.

When employing the drift 30 for removing a pulley such as 14 from the shaft such as 10 as illustrated in Fig. 1, the face 38 is positioned in contact with the surface of the shaft 10 between the hub of the pulley 14 and the sleeve 24 with the sharp edge 40 bearing against the hub of the pulley 14, in the same manner as previously explained and for the same purposes. Because of the sharp edge 40 the pressure exerted on the pulley 14 tending to force it axially of the shaft 10 is exerted and a minimum radial distance from the axis of the shaft 10 and pulley 14 and consequently exerts a minimum tendency towards cocking the pulley 14 on the shaft 10. At the same time, because the sharp edge provides substantially the only line of contact between the drift and the pulley 14, it eliminates any tendency of the drift 30 to slip radially outwardly of the shaft 10 along the inner face of the hub of the pulley 14.

The drift 44 illustrated in Fig. 1 between the head 29 of the key 16 and the hub of the pulley 12 is a righthand drift such as illustrated in Figs. 4 and 5. The drift 44 is identical to the drift 30 in all respects except that in cross-sectional configuration it is tapered in an opposite direction. In other words the drift 44 includes a flat bottom face 46 which lies in a plane perpendicular to the planes of the side faces 48 and 50 and out of parallelism with the top face 52. This drift 44 being a righthand drift the right-

hand face 50 is of less thickness than the lefthand face 48, just the reverse from the corresponding faces 34 and 36 of the drift 30, and so as to form a sharp edge 54 along the lefthand edge of the drift as shown. In its application between the pulley 12 and head 29 of the key 16 as in Fig. 1 its side face 48 is placed in contact with the radially outer face of the key 16 between the head 29 and the hub of the pulley 12 with the sharp edge 54 thereof engaging the axially inner face of the head 29 at its point of junction with the body of the key 16 as will be readily appreciated.

In Figs. 6 and 7 a combination drift embodying both features of the above described drifts 30 and 44 is illustrated and in effect it takes the same form as would occur if the drifts 30 and 44 were positioned in side-to-side relationship with the bottom surfaces 32 and 46 thereof arranged in the same plane with the narrow edge surfaces 34 and 50 thereof in contact with each other and with their respective opposite ends in flush relationship with respect to each other, except that in this case it would be formed in one piece. In other words, the drift indicated generally at 60 in Figs. 6 and 7 includes a plane bottom face 62, opposite side faces 64 and 66 arranged in parallel planes perpendicular to the plane of the face 62 and each having equal vertical dimensions uniformly increasing from one end of the drift towards the opposite end of the drift. The top face of the drift 60 in this case is made up of two surfaces 68 and 70, each occupying one-half of the area of such upper face. The angularity between the side face 64 and the top surface 68 in cross-sectional configuration as illustrated in Fig. 7 is less than 90 degrees so as to form a sharp edge 72 and in a similar manner the angularity between the side face 66 and the top surface portion 70 in cross-sectional configuration as illustrated in Fig. 7 is less than 90 degrees so as to form the sharp edge 74. Thus the righthand side of the drift shown in Fig. 6 is equivalent to the lefthand drift 30 illustrated in Figs. 1 and 2 and the lefthand side thereof equivalent to the righthand drift illustrated in Figs. 4 and 5. It will be readily appreciated that the drift 60 may be used in any case where either the drift 30 or the drift 44 may be employed.

Having thus described my invention, what I claim by Letters Patent is:

1. A key drift comprising an elongated metal member the side edges of which are substantially parallel to each other, said member increasing in thickness from one side edge thereof toward the other side edge thereof, the thicker of said side edges being flat, and one of the side faces being perpendicular to the plane of said thicker side edge, said member also increasing in thickness from one end thereof toward the other end thereof.

2. A key drift comprising an elongated metal member having flat side edges arranged in substantially parallel planes and a flat side face arranged substantially perpendicular to the planes of said side edges, the remaining side face of said member being formed to present two flat surfaces intersecting one another medially of the longitudinal centerline of said remaining face and forming a re-entrant angle between them, said member increasing in thickness from one end thereof toward the other end thereof.

FRANCIS J. WOODRUFF.
